JOHN W. HAYWOOD, OF NEW YORK, N. Y., ASSIGNOR TO HORNE ELECTRIC & MANUFACTURING COMPANY, OF JERSEY CITY, NEW JERSEY, A CORPORATION OF NEW JERSEY.

RUNNING-LIGHT SYSTEM AND BOARD.

Application filed August 22, 1923. Serial No. 658,799.

To all whom it may concern:

Be it known that I, JOHN W. HAYWOOD, a citizen of the United States, and resident of the borough of Bronx, county of Bronx, 5 city and State of New York, have invented certain new and useful Improvements in Running-Light Systems and Boards, of which the following is the specification.

The invention relates to running light 10 systems for ships. The invention comprises an improved system wherein each of the ship's signals contains two lamps, as is not uncommon, and in which the circuit branches for the two lamps are controlled 15 jointly by a relay and a switch, in such manner that the switch will complete a path through the coil of the relay and one or other of the branches, according to its position, while the armature of the relay is 20 adapted automatically to complete a path through the switch, remaining in position, to the other branch, upon failure of the lamp then in circuit with the coil. Upon throwing the switch the lamp automatically light- 25 ed by the armature remains burning, because, while the path established by the armature is broken, a path is restored through the coil and the branch containing this lamp. The relay for each of the running 30 lights controls an indicator on the board corresponding to that light; and in addition there is a common alarm the circuit of which is branched to each of the relays, so that upon failure of a lamp of any one or 35 more of the lights this alarm is sounded, calling attention to the condition shown by the indicators. Preferably there is a dual indicator on the board for each running light, comprising a lamp and a luminous 40 indicator card, or legend-bearing member, the latter being readable in the dark even if the corresponding indicator lamp should burn out.

In the accompanying drawings forming 45 a part hereof:

Fig. 1 is a front elevation of a four-panel board embodying the invention, with one of the panels removed;

Fig. 2 is a wiring diagram;

Fig. 3 is a cross-section through the frame and one of the panels, the intermediate and major portion of the panel being broken away for economy of space; and

Fig. 4 is a fragmentary side elevation of a relay.

Similar reference numerals indicate like parts in all the figures where they appear.

The board has a main panel 1 and any desired number of panels 1^a, connected, respectively, with different running lights. 60 The panels 1^a are duplicates of each other, and the board illustrated contains three of them, though the number may be varied.

The main panel bears a main double-pole single-throw switch 2, fuses 3, 3^a and a 65 buzzer 4. Each of the panels 1^a has a triple-pole double-throw switch 5, a fuse 6, a relay 7, and a lamp 8. The wiring will now be explained.

The characters 9, 9^a designate the conductors of the supply line, connected with the blades of the double-pole switch 2. Each of the running lights or signals of the ship contains two lamps 10, 10^a, only one of which receives current at a time. It will be 75 sufficient to consider the main circuit, one of the signals and its circuits and devices.

With the main switch 2 closed and the switch 5 of the adjacent panel 1^a in the left-hand position seen in Fig. 1, the circuits may be traced as follows: from line wire 9 and one of the poles of switch 2, to conductor 11 on the panel 1, said conductor having fuse 3 therein, to a main wire 12 on the frame 13 of the board, to conductor 14 85 on the panel 1^a, to the pivot terminal 15 of one of the blades of the switch 5, thence to switch contact 18 at the left, thence by conductor 21 to corresponding contact 18^a at the right, to conductor 22, to connection 23 connected with the armature 24 of the relay 7, by conductor 25 to the coil 26 of this relay, through the coil to conductor 27, to the middle pivot terminal 16 of the switch, through the middle blade to the contact 19 95 at the left, by conductor 28 on the panel 1^a and external conductor 29 to the lamp 10 of the signal, by conductor 30 back to the panel 1^a, by conductor 31 on the panel, containing fuse 6, to conductor 32 on the frame, to main 100 conductor 33 on the frame, back to panel 1, to conductor 34 thereon, to conductor 35 containing fuse 3^a, to the other blade of the switch 2, to the other supply line 9^a.

If the lamp 10 burns out, the circuit 105 through the coil 26 of the relay is broken.

and its armature 24 drops, forming electrical connection with two contacts 36 and 37. Thereby circuits are established as follows. Current still flows as just described 5 up to the connection 23 at the armature of the relay. Thence the current passes through the armature to contact 36, thence by conductor 38 to the pivot terminal 17 of the switch 5, through the upper blade of 10 this switch to contact 20 at the left, by conductor 39 to middle contact 19^a at the right, by conductor 40 on the panel and external conductor 41 to the lamp 10^a, thence back by conductor 30 to the panel, and from this 15 point on as with the circuit previously traced. Lamp 10^a is thus automatically lighted upon the failure of lamp 10.

Another circuit branches from the switch terminal 17 through conductor 42 to indicator lamp 8 on the panel 1^a, which is thus lighted, to conductor 43, to conductors 32 and 33 on the frame, and thence back to the supply line as previously traced. In addition to this indication controlled by the armature 24 of the relay, the dropping of the armature itself gives an indication by moving the word "Burning" away from a window in the relay case and bringing the word "Out" into view, these legends being printed 20 in luminous paint on a suitable card 8^a carried by armature. Thus, a double indication is given, and in case the lamp 8 should be out of order, the armature, or electromagnetic device, controlling its circuit, will 25 still afford a signal which is readily discernible in the dark.

A third circuit can be traced from the contact 37, by way of conductor 44 on the panel 1^a to a main conductor 45 on the 30 frame, to conductor 46 on the panel 1, to the buzzer 4, which is energized, by conductor 47 to the conductor 35 and thence back to the supply line. This alarm or signal is given, therefore, when a lamp of any 35 of the ship's running lights goes out.

Warned by the alarm the person whose duty it is goes to the board and by the indication on one of the panels 1^a is advised as to which of the running lights contains 40 a burned-out lamp. He then throws the switch 5 of this panel to the other position; that is to say if he finds it at the left he throws it to the right, while if at the right he throws it to the left. Either position is 45 a normal position. He then goes to the light and inserts a fresh lamp in place of the defective one.

Assuming that the switch was at the left, as has been described, and that it is thrown 50 to the right, a circuit condition like the one first described is established, and the indicators and alarm are de-energized or restored to normal condition. The circuit by way of the armature 24 and contact 36 55 through the lamp 10^a is broken by the move-

ment of the switch 5 away from contact 20, but another circuit is closed which includes this lamp and the relay coil 26. This circuit includes conductor 14, pivot terminal 15, contact 18^a, conductors 22, conductor 25, 70 coil 26, conductor 27, pivot terminal 16, contact 19^a, conductors 40, 41, lamp 10^a, conductors 30, 31, and so on back to line. The coil 26 being energized, its armature is automatically raised, thus removing the 75 "Out" sign from view and restoring "Burning," and breaking the circuit through the buzzer 4, which ceases to sound.

If now lamp 10^a burns, out, (lamp 10 having been replaced), the circuit through the 80 coil 26 is broken as before, the armature drops, and a circuit is completed from the contact 36, through conductor 38, pivot terminal 17, the upper blade of the switch 5, contact 20^a at the right, conductor 39^a to 85 contact 19, through conductors 28, 29 to lamp 10, back by conductor 30, to conductor 31 on the panel, and so on back to line.

When the switch 5 is again thrown to the left, the circuit is again established through the coil 26 and the branch containing the lamp 10, the armature 24 is restored to its normal condition and the indicators and alarm are also restored to normal condition. 90

The board itself will now be described. The top and bottom members of the frame have internal back flanges or ledges 50. In these are mounted forwardly projecting studs 51, three at top and two at bottom in the case of the panel 1, and three at top 100 and three at bottom in the case of each of the panels 1^a. These studs are clamped to the flanges by collars 52 at the front and nuts 53 in recesses at the back. The collars 52 may be fast on the studs or abut against shoulders thereon. Wire terminal brackets 54 are clamped between the collars 52 and the flanges 50, in electrical connection with the studs. The wires which run along the frame are secured to the terminal brackets by binding screws 55. The precise construction and arrangement of the studs and terminals may, however, be varied, though that illustrated is thought to be especially advantageous. 110

The terminals 56 of the wiring on the panels preferably comprise plates or strips secured to the backs of the panels by screws 115 57. These terminals are located on the board with reference to the corresponding terminals on the frame. In the present construction holes 58 are formed through the panels and their terminals 56, in positions to take over the studs. This done, insulated nuts 59 are screwed on to the projecting threaded ends of the studs, and the panels are thereby clamped to the frame, and their terminals at the same time electrically connected with the terminals on the frame, 120 125 130

without fuss or difficulty. Spring washers 60 may be interposed between the terminals 56 and the collars 52.

What I claim is:

- 5 1. In a running light system, the combination with a main circuit, of two lamps, circuit branches for the two lamps, a relay and a manual switch jointly controlling each of said branches, said switch being movable to complete a path through the coil of the relay and one or other of the branches alternately, while the armature of the relay automatically completes a path through the switch to the other branch upon failure of 10 the lamp then in circuit with the coil.
- 15 2. In a running light system, the combination with a main circuit of two lamps, circuit branches for the two lamps, a relay and a manual switch jointly controlling each of 20 said branches, said switch being movable to complete a path through the coil of the relay and one or other of the branches alternately, while the armature of the relay automatically completes a path through the 25 switch to the other branch upon failure of the lamp then in circuit with the coil, and an indicator operated by said relay.
- 30 3. In a running light system, the combination of a main circuit, a plurality of running light circuits in derivation from said main circuit, each of said running light circuits comprising branches for two lamps, a relay and a manual switch in each of said running light circuits jointly controlling

each of said branches, connections whereby 35 the switch is movable to complete a path through the coil of the relay and one or other of the branches alternately, while the armature of the relay automatically completes a path through the switch to the 40 other branch upon failure of the lamp in circuit with the coil, indicators for the respective running light circuits and operated by the relays thereof, and a common alarm having a circuit controlled by the several relays, any one of which is adapted to connect said alarm circuit to said main circuit.

4. In a running light system, the combination of a main circuit, a plurality of signal lamps, circuit branches for said lamps, a relay and a manual switch jointly controlling each of said branches, connections whereby the switch is movable to complete a path through the coil of the relay and one 50 or other of the branches alternately, while the armature of the relay and contacts closed thereby complete a path through the switch to the other branch upon failure of the lamp then in circuit with the coil and dial indicators for the respective running light circuits comprising an indicator lamp and circuit controlled through the armature and contacts of said relay and an indicator card mechanically connected to the relay. 55

New York city, N. Y., July 31, 1923. 60

JOHN W. HAYWOOD.
